(57) **CLAIM**

I claim the ornamental design for a wall hung hair drier, as shown and described.

DESCRIPTION

FIG. 1 is a perspective view of a wall hung hair drier showing my new design;

FIG. 2 is a front elevational view of the wall hung hair drier as shown in FIG. 1;

FIG. 3 is a right elevational side view of the wall hung hair drier as shown in FIG. 1;

FIG. 4 is a left elevational side view of the wall hung hair drier as shown in FIG. 1;

FIG. 5 is a rear elevational view of the wall hung hair drier as shown in FIG. 1;

FIG. 6 is a top view of the wall hung hair drier as shown in FIG. 1; and,

FIG. 7 is a bottom view of the wall hung hair drier as shown in FIG. 1.
